TREATMENT OF HYDROCARBON OILS

Jacque C. Morrell, Chicago, Ill., assignor to Universal Oil Products Company, Chicago, Ill., a corporation of South Dakota

Application May 20, 1931, Serial No. 538,698

4 Claims. (Cl. 196—60)

This invention relates to the treatment of hydrocarbon oils and particularly refers to the conversion of relatively heavy oils into more valuable products of a lighter and lower boiling nature.

5 Primarily, the invention comprises subjecting raw oil charging stock to relatively mild conversion conditions in a cracking system, subjecting insufficiently converted intermediate products from this conversion to further conversion under 10 more severe cracking conditions and returning insufficiently converted intermediate products resulting from the secondary cracking operation to reconversion in the primary cracking system.

A more specific embodiment of the invention 15 may comprise supplying raw oil charging stock to relatively mild conversion conditions in a heating element, introducing the heated oil into an enlarged reaction zone in which vapors and residual liquid may be separated, subjecting the 20 vapors to fractionation in a primary fractionating zone, reflux condensate from which may be returned to said heating element together with the raw oil charging stock, subjecting vapors from the primary fractionating zone to further 25 fractionation in a secondary fractionating zone, subjecting vapors from said secondary fractionating zone to condensation and cooling, and collecting the resulting products, subjecting residual oil from the reaction chamber to further vaporization in a zone of reduced pressure, subjecting 30 vapors from said zone of reduced pressure together with reflux condensate from the aforementioned secondary fractionating zone to further conversion, preferably under relatively severe 35 conversion conditions in a separate heating element, introducing reconverted materials from said separate heating element into a separate fractionating zone, vapors from which may pass to the aforementioned secondary fractionating zone and reflux condensate from which may be returned to the first mentioned heating element together with raw oil charging stock and reflux condensate from the primary fractionating zone.

The attached diagrammatic drawing illustrates 45 one form of apparatus embodying the principles and features of the present invention. The following description of the drawing embraces also a description of the process of the invention as it may be practiced in the apparatus illustrated.

50 Raw oil charging stock may be supplied through line 1 and valve 2 to pump 3 from which it may be fed through line 4, line 5, valve 6, and line 7 into heating element 8. If desired, a portion or all of the raw oil charging stock may be fed 55 through valve 9, in line 4, into fractionator 10,

being thereby preheated by the relatively hot vapors in this zone which it may assist to fractionate and passing together with the relatively heavy condensed components of the vapors through line 11 and valve 12 to pump 13 which may supply the reflux condensate from this zone, alone or together with preheated raw oil, as the case may be, through line 14, valve 15 and line 7 to heating element 8. Likewise, a portion or all of the raw oil charging stock may, if desired, be diverted from line 5 through line 16 and valve 17 into fractionator 18 where it may assist fractionation of the vapors and from which it may pass together with their relatively heavy condensed components through line 19 and valve 20 to pump 15 21. The reflux condensate from fractionator 18, alone or together with preheated raw oil, as the case may be, may be fed by means of pump 21 through line 22, valve 23 and lines 5 and 7 to heating element 8.

The oil supplied to heating element 8 may be heated to the desired conversion temperature under any desired pressure conditions by heat supplied by any suitable furnace 24. The heated oil may be discharged through line 25 and valve 26 into reaction chamber 27. Preferably, heating element 8 and chamber 27 are maintained under a substantial superatmospheric pressure and the pressure employed in chamber 27 may be substantially the same or lower than that utilized 30 in the heating element. Vapors may be separated from residual oil in chamber 27 and may be withdrawn through line 28 and valve 29 to fractionation in fractionator 18. The relatively heavy components of the vapors condensed in this zone 35 are preferably returned, as already described, to heating element 8 for further conversion. Vapors from fractionator 18 may pass through line 30 and valve 31 to further fractionation in fractionator 32.

The relatively light fractionated vapors of the desired composition may pass from fractionator 32 through line 33 and valve 34, may be subjected to condensation and cooling in condenser 35, distillate and uncondensable gas from which 45 may pass through line 36 and valve 37 to be collected in receiver 38. Uncondensable gas may be released from the receiver through line 39 and valve 40. Distillate may be withdrawn through line 41 and valve 42. A portion of the distillate 50 may, if desired, be recycled by well known means (not shown) to any or all of the fractionators 32, 18 and 10 to assist fractionation of the vapors in these respective zones.

Residual oil may be withdrawn from chamber 55

27 through line 43 and valve 44 to chamber 45 which is preferably maintained under a substantially reduced pressure relative to that employed in chamber 27 and wherein the residual oil may be subjected to further vaporization. The final residual liquid product, if such is produced, may be withdrawn from chamber 45 through line 46 and valve 47. If desired, conditions may be so controlled in chamber 45 that only substantially dry coke or carbonaceous material will remain as the residual product and this may be collected in the chamber to be removed after the operation of the process is discontinued. If desired, a plurality of such chambers (not shown) may be employed for non-residuum operation and may be operated alternately or simultaneously to permit prolonged operation of the process.

Vapors from chamber 45 may pass through line 48 and valve 49 to pump 50 from which they may be fed through line 51 and valves 52 and 53 into heating element 54. In case a substantially higher pressure is utilized in chamber 45 than that employed in heating element 54, pump 50 may be by-passed by directing the vapors through line 63 and valve 64, valves 49 and 52 being closed. The relatively heavy insufficiently converted components of the vapors which are subjected to fractionation in fractionator 32 may be condensed in this zone, may pass through line 55 and valve 56 to pump 57 from which they may be fed through line 58 and valve 59 into line 51, commingling therein with the vapors from chamber 45 and passing therewith to heating element 54.

Heating element 54 may be located within any suitable form of furnace 60 and the oil passing therethrough may be heated to the desired conversion temperature under any desired pressure conditions. Preferably more severe conversion conditions are employed in heating element 54 than those utilized in heating element 8 and, if desired, conditions within the range of vapor-phase cracking may be utilized. Heated products may be discharged from the heating element 54 through line 61 and valve 62 into the lower portion of fractionator 10 in which any heavy polymerization products or the like may be separated from the vapors. Liquid accumulating in fractionator 10 which may comprise the relatively heavy condenser components of the vapors subjected to fractionation in this zone, any residual liquid or polymerization products and preheated raw oil, if any portion of the raw oil is supplied to this zone, may be returned as already indicated through line 11, valve 12, pump 13, line 14, valve 15 and line 7 to heating element 8. Fractionated vapors from fractionator 10 may pass through line 63 and valve 64 to fractionator 32 to be subjected to further fractionation and the same subsequent treatment as that afforded the vapors from fractionator 18.

Pressures employed within the system may range from substantially atmospheric to superatmospheric pressures as high as 2,000 pounds per square inch, or more. Conversion temperatures employed may range from 800 to 1200° F., more or less. Preferably substantial superatmospheric pressures of the order of 100 to 500 pounds per square inch are employed in the heating element and reaction chamber of the primary or liquid-vapor-phase system, while the conversion temperatures in the heating element of this system may range from 850 to 950° F., more or less.

Pressures substantially equalized with that employed in the reaction chamber or reduced pressures of the order of substantially atmos-

pheric to 100 pounds per square inch superatmospheric pressure, or thereabouts may be employed in the fractionating, condensing and collecting equipment of the system. Reduced pressures of the order of substantially atmospheric to 60 pounds per square inch, or more, superatmospheric pressure are preferably employed in the residuum flash distilling chamber. The secondary or vapor-phase conversion system preferably employs pressures of the order of substantially atmospheric to 150 pounds per square inch superatmospheric pressure and conversion temperatures of the order of 950 to 1200° F., more or less.

As a specific example of the operation of the process of the present invention, as it may be practiced in an apparatus such as illustrated and described, a 24° A. P. I. gravity fuel oil is the raw oil charging stock and it is subjected together with reflux condensate from the primary fractionator and reflux condensate from the fractionator of the vapor-phase system to a temperature of approximately 910° F. under a superatmospheric pressure of about 250 pounds per square inch. This pressure is substantially equalized within the reaction chamber and primary fractionator, is reduced in the secondary fractionator to a pressure of about 100 pounds per square inch and in the residuum flash distilling zone to a pressure of about 30 pounds per square inch. Reflux condensate from the secondary fractionator and vapors from the flash distillation of the residual oil are subjected to a temperature of approximately 1050° F. under a superatmospheric pressure of about 100 pounds per square inch.

This operation may yield approximately 65% of motor fuel having an anti-knock value approximately equivalent to a blend of 60% benzol and 30% straight-run Pennsylvania gasoline. In addition about 23% of marketable fuel oil may be produced, the only other products of the process being rich uncondensable gas and a small percentage of coke or carbonaceous material.

I claim as my invention:

1. A hydrocarbon oil cracking process which comprises subjecting the oil to cracking conditions of temperature and pressure in a cracking zone and separating the same into vapors and unvaporized oil, subjecting the vapors to primary and secondary dephlegmation thereby forming relatively heavy and light reflux condensates, returning the heavy reflux condensate to said cracking zone for retreatment therein, flash distilling the unvaporized oil by pressure reduction, combining resultant flashed fractions with the light reflux condensate and cracking the mixture in a second cracking zone maintained at higher cracking temperature than the first-mentioned cracking zone, dephlegmating the vapors formed in said second cracking zone, and returning resultant reflux to said first-mentioned cracking zone, and finally condensing the dephlegmated vapors.

2. A hydrocarbon oil cracking process which comprises subjecting the oil to cracking conditions of temperature and pressure in a cracking zone and separating the same into vapors and unvaporized oil, subjecting the vapors to primary and secondary dephlegmation thereby forming relatively heavy and light reflux condensates, returning the heavy reflux condensate to said cracking zone for retreatment therein, flash distilling the unvaporized oil by pressure reduction, subjecting the flashed vapors to vapor phase cracking in admixture with the light reflux condensate,

5 dephlegmating the vapor phase cracked vapors and returning resultant reflux to said first-mentioned cracking zone, and finally condensing the dephlegmated vapors.

10 3. A hydrocarbon oil cracking process which comprises subjecting the oil to cracking conditions of temperature and pressure in a cracking zone and separating the same into vapors and unvaporized oil, subjecting the vapors to primary and secondary dephlegmation thereby forming relatively heavy and light reflux condensates, returning the heavy reflux condensate to said cracking zone for retreatment therein, flash distilling the unvaporized oil by pressure reduction, combining resultant flashed fractions with the light reflux condensate and cracking the mixture in a second cracking zone maintained at higher cracking temperature than the first-mentioned cracking zone, dephlegmating the vapors formed in said second cracking zone, and returning resultant reflux to said first-mentioned cracking zone, further dephlegmating the last-named vapors in admixture with the vapors undergoing secondary dephlegmation whereby the lighter in-

sufficiently cracked fractions thereof are added to said light reflux condensate.

15 4. A hydrocarbon oil cracking process which comprises subjecting the oil to cracking conditions of temperature and pressure in a cracking zone and separating the same into vapors and unvaporized oil, subjecting the vapors to primary and secondary dephlegmation thereby forming relatively heavy and light reflux condensates, 10 returning the heavy reflux condensate to said cracking zone for retreatment therein, flash distilling the unvaporized oil by pressure reduction, subjecting the flashed vapors to vapor phase cracking in admixture with the light reflux condensate, dephlegmating the vapor phase cracked vapors and returning resultant reflux to said first-mentioned cracking zone, further dephlegmating the last-named vapors in admixture with the vapors undergoing secondary dephlegmation 15 whereby the lighter insufficiently cracked fractions thereof are added to said light reflux condensate.
